US00D928287S

(12) **United States Design Patent** (10) **Patent No.:** **US D928,287 S**
Svendsen et al. (45) **Date of Patent:** **** Aug. 17, 2021**

(54) **NOZZLE**(71) Applicant: **MELNOR, INC.**, Winchester, VA (US)(72) Inventors: **Sean Wesley Svendsen**, Columbus, OH (US); **Donald Collins Meves**, Columbus, OH (US); **Eric James Fickas**, Plain City, OH (US)(73) Assignee: **Melnor, Inc.**, Winchester, VA (US)(***) Term: **15 Years**(21) Appl. No.: **29/718,888**(22) Filed: **Dec. 30, 2019****Related U.S. Application Data**

(62) Division of application No. 29/670,354, filed on Nov. 15, 2018, now Pat. No. Des. 874,612, which is a division of application No. 29/598,175, filed on Mar. 23, 2017, now Pat. No. Des. 839,992.

(51) **LOC (13) Cl.** **23-01**(52) **U.S. Cl.**USPC ..... **D23/223**(58) **Field of Classification Search**

USPC D23/226, 213, 223, 224

CPC B05B 1/12

Primary Examiner — Kevin K Rudzinski(74) *Attorney, Agent, or Firm* — HEA Law PLLC; Darrin A. Auito(57) **CLAIM**

The ornamental design for a nozzle, as shown and described.

DESCRIPTION

FIG. 1 is a rear perspective view of a nozzle, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front perspective view thereof.

The broken line showing of portions of the nozzle is for the purpose of illustrating environmental structure and forms no part of the claimed design.

1 Claim, 6 Drawing Sheets(56)
